BINARY CYCLE POWER PLANT HAVING A
HIGH MELTING POINT TERTIARY FLUID
FOR INDIRECT HEATINGLeonard R. Biggs, Schenectady, N. Y., assignor to
General Electric Company, a corporation of
New York

Application January 11, 1950, Serial No. 137,993

5 Claims. (Cl. 60—38)

1

This invention relates to thermal powerplants, particularly to a powerplant of the type having three separate fluid circuits, one of which is charged with a liquid which never reaches its boiling point, while the other two contain suitable liquids of a type which pass through liquid and vapor phases as in more conventional elastic fluid turbine powerplants.

An object of the invention is to provide a thermal powerplant especially adapted to extract thermal energy from a heat releasing reaction of extremely high intensity and occupying a comparatively small volume, and converting this thermal energy to mechanical energy with the maximum possible efficiency. Another object is to provide a thermal powerplant of the type described in which the primary liquid circuit includes only a single supply conduit and a single return conduit connecting a primary heating device with heat exchangers which transfer energy to the secondary and tertiary fluid circuits, so that the secondary and tertiary circuits with their respective heaters may be located at a considerable distance from the heat generating reaction, without complex piping therebetween. A still further object is to provide a three fluid powerplant in which the components operating at the highest temperature levels in the cycle also operate at a low pressure, so that the mechanical strength and life of the components may be adequate. Another object is to provide an improved powerplant arrangement having even greater thermal efficiency than previously known binary fluid powerplants, yet requiring a smaller charge of operating liquid.

Other objects and advantages will be apparent from the following description taken in connection with the accompanying drawing in which the single figure represents schematically the arrangement of a three fluid powerplant in accordance with the invention.

Referring now more particularly to the drawing, the heat generating reaction is represented to be the combustion of a suitable fuel in a boiler indicated generally at 1 as including a combustion chamber 2 lined with boiler tubes 3 and having a suitable fuel burning device 4. Combustion air is supplied by a forced draft fan 5 through an air pre-heater 6 in accordance with conventional practice. The flue gases are drawn from the combustion space through a liquid pre-heater or "economizer" 7 and the air pre-heater 6 by an induced draft fan 8. While this rather conventional type of boiler arrangement has been disclosed for purposes of illustration, it is to be noted

2

that the present powerplant is particularly adapted for extracting and converting thermal energy from heat generation devices of much more compact design which liberate energy at rates far exceeding those found in the ordinary steam boiler. For instance, a gas turbine combustor of the general type disclosed in the copending application of A. J. Nerad, Serial No. 750,015, filed May 23, 1947, and assigned to the same assignee as the present application, might well be used as the heat generating device. In such a combustor, heat release "space rates" well above 5,000,000 B. t. u. per hour per cubic foot of combustion space volume may be obtained. Other heating means of very high intensity types will occur to those skilled in the art.

The primary fluid circuit is indicated by the solid arrows in the drawing. It is to be particularly noted that this primary circuit is charged with a material which remains liquid in all parts of the circuit, the temperatures in the heat generator being below those required to boil the material. This charge may consist of liquid sodium metal, which melts at 208° F., or any one of several known mixtures of sodium salts, such as those previously used in the so-called "salt-cooled" exhaust valves of internal combustion engines. It is also to be particularly noted that the pressure in this primary circuit is comparatively low, the static pressure being only that resulting from the hydraulic head due to differences in level of the various parts of the circuit. To keep the primary circuit charged and to insure that the pressure does not rise above the static head of the liquid in the circuit, a surge tank shown at 9 is provided. This is maintained at atmospheric pressure by means of the bellows 9a which freely provides expansion room to accommodate changes in volume of the liquid charge as the operating temperature varies, without creating pressures above atmospheric pressure. If the primary liquid is of a type which does not decompose in contact with oxygen, the surge tank 9 may simply be vented to the atmosphere.

45 The heat released in the combustion space 2 is transferred to the primary liquid in the heat generator tubes 3 and extracted in a primary heat exchanger consisting of a series of four heat exchange devices in series flow relation. It will be apparent that the hot primary liquid enters the top of the first heat exchange device 11, then flows progressively downward through the second heat exchange device 12, the third heat exchange device 13, and the fourth heat exchange device 14, from which it is caused to circulate by the pri-

mary liquid circulating pump 15 through the return conduit 16. Conduit 16' conducts the cool liquid through the economizer 7, from which it enters the upper header 3a communicating with the respective heater tubes 3. It will be observed that the cool liquid flows downwardly through the tubes 3 in counter-flow relation with the hot gases in the combustion space 2. The hot liquid is collected by the lower header 3b which communicates with the supply conduit 10.

It will be observed that the piping connecting the heat generator with the primary heat exchanger is extremely simple, consisting of only one supply pipe and one return pipe. Thus the primary heat exchanger can be located immediately adjacent the turbines and their auxiliary equipment, while the heat generator may be conveniently located at a considerable distance from the rest of the powerplant. This means that a minimum amount of very simple piping is required between the heat generator and the heat converting equipment.

A number of important advantages may be noted in connection with the primary liquid circuit of this powerplant. In the first place, the heat transfer from the combustion gases to the primary fluid is of optimum efficiency since the liquid never boils in the primary circuit. This means that the highest efficiency is obtained from the counterflow heat exchange process in the heater 1, since the temperature of the liquid increases progressively as it flows downwardly, while the hot gas temperature decreases progressively as it flows upwardly past the heater tubes 3. This is in sharp contrast with the usual steam or mercury boiler, in which there is a certain location in the tubes where the liquid phase changes to the vapor phase, at which point considerable heat energy is absorbed without any change in temperature. This introduces an inherent loss of efficiency, which is avoided with the present arrangement. Thus the present arrangement eliminates a serious irreversibility which introduces substantial inherent losses in the thermal cycles of previously known mercury and steam turbine powerplants. Furthermore, the heat transfer process from the hot gases through the metal walls of the tubes 3 to the liquid within the tubes is much more efficient than the more usual transfer of heat from combustion gases through boiler tubes to a fluid which may be partly liquid, partly vapor, and sometimes a mixture of the two.

It may also be noted that the sodium or sodium salt mixture used as the primary liquid is much lower in cost than the mercury charge used in previously known binary fluid powerplants. Likewise, because of the more efficient heat transfer, the heat generating equipment may be smaller in size and therefore cheaper.

A most important advantage lies in the fact that the primary fluid circuit, which operates at the highest temperatures occurring in the cycle, at the same time operates at a comparatively low pressure. Whereas in a mercury boiler of conventional arrangement, the boiler tubes may be required to operate at pressures in the neighborhood of 500 pounds per square inch, the static pressures existing in the present system may be only on the order of 50 pounds per square inch gage, and even this high a pressure will exist only in a portion of the tubes at the lower levels in the primary circuit. Therefore, because the mechanical stresses due to pressure within the tubes are comparatively low in those portions of

the circuit where the thermal stresses are highest, the heat transfer tubes and hot liquid conduits may be more conveniently designed to have adequate strength and life, with reasonable safety factors.

The secondary fluid circuit is represented by the dashed arrows in the drawing and comprises a mercury vapor turbine indicated at 16 as being of the well-known "double-flow" type. After giving up some of its energy in the turbine rotor 16a, the mercury vapor serves to heat a fifth heat exchanger 17, a sixth heat exchanger 18, and a seventh heat exchanger 19. It will be appreciated by those skilled in the art that these heat exchangers 17, 18, 19 may be conveniently located within an exhaust casing common to the turbine 16. Liquid mercury is withdrawn from the bottom of the turbine casing by a circulating pump 20, whence it flows through conduit 21 to heat exchanger 18, which serves as a mercury liquid pre-heater. From the pre-heater 18, the liquid mercury flows through conduit 22 to the second heat exchanger 12 which further pre-heats the liquid, the mercury flowing through heater 12 in counter-flow relation with the primary fluid. From pre-heater 12, the liquid mercury flows through conduit 23 through the first heater 11, again in counter-flow relation with the primary fluid. The heater 11 is, of course, the "boiler" for the mercury cycle, from which mercury vapor passes through conduit 24 to the inlet of the mercury turbine 16. In accordance with conventional practice, a separator drum 25 may be arranged so that any liquid particles in the conduit 24 will return to the inlet side of the heater 11.

It will be observed that this arrangement of the mercury cycle facilitates placing the heaters 11, 12 immediately adjacent the mercury turbine 16, and as noted before the heaters 17, 18, 19 are integral parts of the mercury turbine unit. Thus the mercury portion of the cycle can contain a liquid charge of comparatively small weight, which means that much less of the comparatively expensive mercury is required than is the case in conventional mercury powerplants. Likewise, the piping conveying hot mercury from heaters to turbine is comparatively short, thus reducing the complexity and cost of the high temperature piping, also reducing the probability of accidentally releasing mercury into the atmosphere which would constitute a serious health hazard.

The tertiary fluid circuit is indicated by the dotted arrows in the drawing. This comprises a high pressure steam turbine 26 in series with a low pressure turbine 27. The turbine 26 is of the extraction type, the steam extracted through conduit 28 serving as the heating medium in an extraction heater 29, as described more particularly hereinafter. After passing through the rotor 27a of the low pressure turbine, the exhaust steam passes through a feed-water heater 30 and then into the steam condenser 31. Condenser 31 is of conventional construction, having a suitable coolant pump 32 for circulating water at a low temperature through the intake conduit 32a and out the discharge conduit 32b. It will be noted that the heat transferred to the cooling water in the condenser 31 is the only thermal energy rejected in this system, aside from the usual radiation losses, and, of course, the sensible heat in the flue gas from the furnace 1. Also associated with condenser 31 is a hot-well or circulating pump 33 which supplies condensate to a boiler feed pump 34. In accordance with conventional practice, a suitable type of air ejector 35 may be provided to

remove any entrained air from the condensate. Also, there may be provided in cooperation with the boiler feed pump 34, as indicated diagrammatically at 36, a "de-aerating heater," the heating medium for which is steam extracted through conduit 37 from the exhaust casing of the high pressure turbine 26. Condensed heating fluid from the extraction heater 29 drains to the de-aerating heater 36 through conduit 38. A suitable surge tank 39, vented to the atmosphere, insures an adequate supply of liquid to the boiler feed pump, and provides expansion room for changes in volume of the hot water in the system.

It will now be apparent from the drawing that the hot-well pump 33 supplies water through the 15 air ejector 35 to the feed-water heater 30, thence to the de-aerating heater 36 and the boiler feed pump 34. Pump 34 circulates liquid through the extraction pre-heater 29, thence to the mercury "condenser-boiler" 19, which may be provided with a separator drum 19a. From this separator, steam passes by way of conduit 42 to the fifth heat exchanger which serves as an "extraction super-heater," whence the super-heated steam passes through conduit 43 to the third heat exchanger 13 where it absorbs further heat in counter-flow relation with the primary fluid. From heat exchanger 13, the highly super-heated steam passes by way of conduit 44 to the inlet of the high pressure turbine 26. The principal portion of steam exhausted from turbine 26 passes by way of conduit 45 to the fourth heat exchanger 14, which serves as a "reheater" supplying motive fluid through conduit 46 to the inlet of the low pressure turbine 27.

It will be apparent from the above description that this novel powerplant arrangement provides the most efficient form of counter-flow heat exchange in the heat generator 1 because the primary fluid remains liquid throughout the heater, while at the same time thermal energy is transferred from the primary liquid to the secondary and tertiary fluids in a series of heat exchangers which are also arranged for most effective utilization of the counter-flow principle. It will also be observed that the primary liquid works at extremely high temperatures but low pressures, the tertiary fluid operates at high pressures, while the secondary fluid operates at intermediate pressures and temperatures. Thus, in general, it can be said that no component in the system is exposed to both extremely high temperature and extremely high pressure conditions.

In the arrangement shown in the drawing, the mercury turbine 16 and the high and low pressure steam turbines 26, 27 are all geared to a common load device, shown as an electrical generator 47. The reduction ratios between the respective pinions 27b, 26a, and 16b are so selected that the high pressure steam turbine rotor operates at a speed in the neighborhood of 5,000 R. P. M., the low pressure turbine operates at an intermediate speed in the neighborhood of 1,800 R. P. M., while the mercury turbine runs at a speed in the neighborhood of 900 R. P. M. Thus the three different types of turbines are permitted to operate at their most efficient speeds although geared at fixed ratios to a common load device.

It will also be observed that the optimum use has been made of the pre-heating principle in 70 connection with the tertiary fluid. That is, the feed-water pumped into the mercury condenser-boiler first picks up heat, at a comparatively low temperature level, from the exhaust steam of the low pressure turbine 7 in the pre-heater 30, then

acquires additional heat at a higher temperature level from the extraction steam from turbine 26 in the extraction heater 29, and finally is caused to evaporate in the condenser-boiler 19.

It will be apparent to those skilled in the art that the powerplant described inherently has very high efficiency because heat energy is added to the primary liquid at an extremely high temperature level in a generator of comparatively small size, so that radiation losses may be minimized, while this thermal energy is transferred from the primary circuit to secondary and tertiary working fluids at progressively lower temperature levels. Also, except for the usual radiation and stack losses, the only rejection of heat from the cycle is to the condenser cooling water, at a comparatively low temperature level. Throughout the system, optimum use is made of the counter-flow heat transfer principle, both in transferring heat from the hot reaction products to the primary heat transfer fluid, from the primary fluid to the secondary and tertiary working fluids, and from various portions of the working fluid to the liquids at the 25 "cold" sides of the working circuits. The resulting powerplant promises to effect an overall thermal efficiency substantially greater than that of previously known binary cycles using mercury and steam while at the same time necessitating a much smaller charge of the comparatively expensive mercury.

While the invention has been described as having fluid circuits charged with sodium salts or liquid sodium metal, mercury, and water, it will be appreciated that other suitable operating liquids might be used, for instance, the high-boiling point diphenyl compositions known to the trade as "Dow-Therm," the low-boiling chlorinated-fluorinated aliphatics known commercially as "Freon," etc.

It will be obvious to those skilled in the art that many other minor alterations and substitutions of equivalent fluids and components might be made in the specific embodiment of the invention disclosed herein, and it is desired to cover by the appended claims all such modifications as fall within the true spirit and scope of the invention.

What I claim as new and desire to secure by Letters Patent of the United States is:

1. In a three fluid thermal powerplant, the combination of conduits defining a primary liquid circuit charged with a material which remains liquid at all normal operating temperatures and has a boiling point substantially above the maximum temperature in the cycle and including a primary heater connected by one supply conduit and one return conduit to a primary heat exchanger, the latter comprising first heat exchange means for a secondary fluid circuit and second heat exchange means for a tertiary fluid circuit; conduits defining a secondary fluid circuit charged with a high-boiling liquid and including an elastic fluid turbine having in the exhaust conduit therefrom a secondary liquid pre-heater receiving heat from the spent secondary fluid and a condenser-boiler for condensing the secondary vapor, and conduit means with a circulating pump for passing secondary liquid from the condenser-boiler through the liquid pre-heater and then through the first heat exchange means in counter-flow relation with the primary liquid, the secondary fluid vapor from the first heat exchange means returning to the inlet of the turbine; and conduits defining

a tertiary fluid circuit charged with a comparatively low-boiling liquid and including a high pressure and a low pressure elastic fluid turbine in series flow relation with a second liquid pre-heater disposed in a second condenser receiving fluid exhausted from the low pressure turbine, and conduit means with a circulating pump for passing condensate from the tertiary fluid condenser through the second liquid pre-heater; thence through the secondary liquid condenser-boiler and through the third heat exchange means in counter-flow relation with the primary fluid and to the inlet of the high pressure turbine.

2. In a three fluid thermal powerplant, the combination of a primary fluid circuit including a primary heater and primary heat exchanger means with only one high temperature conduit connecting the heater with the exchanger and only one lower temperature return conduit to the heater, the primary circuit being charged with a primary liquid having a boiling point substantially above the maximum normal operating temperatures, a surge tank connected to the primary circuit and maintained substantially at ambient atmospheric pressure whereby the maximum pressure in the primary circuit is only that of the hydraulic head of the liquid in said circuit, the primary heat exchanger including first, second, third, and fourth heat exchange devices in series flow relation, with the first device receiving the hot primary liquid through the supply conduit directly from the heater and the fourth device discharging to the return line; a secondary fluid circuit including a first elastic fluid pressure turbine, said secondary circuit being charged with a high-boiling fluid and closed to the atmosphere, fifth, sixth, and seventh heat exchange devices associated with the first turbine and adapted to extract heat from motive fluid exhausted therefrom, a secondary fluid circulating pump, and conduits defining a circuit for the secondary fluid from the circulating pump through the sixth heat exchange device then through the second and first heat exchange devices serially and in counter-flow relation with the primary liquid, the secondary fluid vapor from the hot discharge end of the first heat exchange device returning to the inlet of the first turbine; and a tertiary fluid circuit charged with a comparatively low-boiling fluid and including a second high pressure elastic fluid turbine of the extraction type, and a third low pressure turbine having heated by the exhaust therefrom an eighth heat exchange device and a condenser for rejecting heat at the lowest temperature in the cycle to a coolant fluid, said third fluid circuit including also condensate circulating and boiler feed pump means and a ninth heat exchange device heated by high temperature fluid extracted from the second turbine, and conduit means arranged to pass condensate from the condenser through the eighth heat exchange device in counter-flow relation with fluid exhausted from the third turbine, thence through the boiler feed pump and the ninth heat exchange device, then through the seventh heat exchange device in counter-flow relation with the secondary fluid vapor exhausted from the first turbine, thence through the fifth heat exchange device, and through the third heat exchange device in counter-flow relation with the primary liquid, thence to the inlet of the second turbine, the exhaust from the second turbine going through the fourth heat exchange device in counter-flow

relation with the primary liquid and thence to the inlet of the third turbine.

3. A thermal powerplant in accordance with claim 2 in which the secondary fluid turbine and the high and low pressure tertiary fluid turbines are all geared to drive a common load output device, the gear ratios being such that the secondary fluid turbine operates at a comparatively low speed, the low pressure tertiary fluid turbine operates at an intermediate speed, and the high pressure turbine operates at a high speed.
4. In a three fluid thermal powerplant, the combination of a primary liquid circuit charged with a material which is liquid at normal operating temperatures and has a boiling point substantially above the maximum temperature in the cycle and including a primary heater connected by one supply conduit and one return conduit to a primary heat exchanger comprising first heat exchange means for the secondary fluid circuit and second heat exchange means for the tertiary fluid circuit, the secondary circuit being charged with a high-boiling liquid and including an elastic fluid turbine, a liquid pre-heater associated with the secondary fluid turbine and adapted to be heated by the exhaust vapor therefrom, and a condenser-boiler for condensing secondary fluid in the secondary circuit and transferring heat to the tertiary circuit; and conduit means with a circulating pump for passing secondary liquid from the condenser-boiler through said preheater and then through the first heat exchanger in counter-flow relation with the primary liquid, vapor from the first heat exchange means returning to the inlet of the secondary fluid turbine, the tertiary circuit being charged with a lower-boiling liquid and including a high pressure and a low pressure elastic fluid turbine in series flow relation with a tertiary fluid condenser receiving fluid from the low pressure turbine, circulating pump means with conduit means for passing condensate from the tertiary fluid condenser to the secondary fluid condenser-boiler; then through the third heat exchange means in counter-flow relation with the primary fluid and to the inlet of the high pressure turbine.
5. A three fluid thermal powerplant comprising conduits defining a primary liquid circuit charged with a material which is liquid at all normal operating temperatures and has a boiling point substantially above the maximum temperature in the cycle, conduits defining a secondary fluid circuit charged with a high-boiling liquid, and conduits defining a tertiary circuit charged with a lower-boiling liquid, the primary circuit including a primary heater connected by one supply conduit and one return conduit to first heat exchange means adapted to vaporize the liquid in the secondary circuit, means in the primary circuit for preventing the static pressure therein from rising substantially above ambient atmospheric pressure whereby the high temperature primary circuit is maintained at a comparatively low pressure, the secondary circuit including an elastic fluid turbine having associated with the exhaust therefrom a condenser-boiler adapted to condense the secondary fluid in the secondary circuit and vaporize liquid in the tertiary circuit, the secondary circuit also including pump means for passing liquid from the secondary fluid condenser through the first heat exchanger in counter-flow relation with the primary liquid, conduits for passing secondary fluid vapor from the first heat exchanger to the inlet of the secondary fluid turbine, the tertiary circuit being charged with a

comparatively low-boiling liquid and including at least one elastic fluid turbine having a condenser for receiving the exhaust therefrom, circulating pump means in the tertiary circuit with conduit means for passing condensate from the tertiary fluid condenser to the secondary fluid condenser-boiler, and conduit means for passing tertiary fluid generated in the condenser-boiler to the inlet of the tertiary fluid turbine.
